[57] **CLAIM**

The ornamental design for a suction inlet bowl for a submersible pump, as shown and described.

DESCRIPTION

FIG. 1 is an elevational view of a suction inlet bowl for a submersible pump embodying my new design.

FIG. 2 is an elevational view showing the diametrically opposite side thereof.

FIG. 3 is an elevational view thereof looking from the right hand side of FIG. 1, the left hand side being a mirror image thereof.

FIG. 4 is a top plan view thereof.

FIG. 5 is a bottom plan view thereof.

FIG.1

FIG.2

FIG. 3

FIG. 4
